UNITED STATES PATENT OFFICE.

JOHN WAHL AND OTTO MELZER, OF BROOKLYN, NEW YORK, ASSIGNEES TO A. SCHRADER'S SON, INC., OF BROOKLYN, NEW YORK, A CORPORATION OF NEW YORK.

WRENCH MECHANISM.

Application filed January 7, 1925. Serial No. 1,025.

This invention relates to a wrench mechanism and aims to provide certain improvements therein.

The object of the invention is to provide 5 a power operable wrench for quickly screwing up nuts on the screw-threaded body portion of a straight or curved valve stem or the like. A further object of the invention is to provide means for properly aligning the 10 bridge washer with relation to the pneumatic tube and the bent arm of a valve stem, when such valve stem is being secured to the tube.

With these and other objects in view, the 15 invention consists of a driving wrench adapted to be driven by any source of motive power, means for engaging and holding a valve stem against rotation while the driving wrench runs a nut up on the valve stem, 20 and means for aligning and properly positioning the bridge washer with relation to the pneumatic tube and the bent arm on a valve stem comprising means for holding the bridge washer against rotation.

25 A preferred embodiment of our invention is shown in the accompanying drawings wherein,—

Figure 1 shows an axial section of a wrench mechanism embodying our invention.

30 Fig. 2 shows a transverse section of the device taken on the line 2—2 of Fig. 1.

Fig. 3 shows a transverse section taken on the line 3—3 of Fig. 1.

Fig. 4 shows in elevation the bridge washer 35 holding means.

Referring to the drawings, the wrench mechanism comprises a base or supporting member A provided with suitable bearings B and C, within which is mounted a drive 40 mechanism D which operates the driving wrench E.

The drive mechanism D may be of any construction, preferably of the adjustable yielding type, and, as herein shown, consists of a cone clutch, one element of which is a pulley F, one face of which is cut away to provide the conical face G, and the other is a laterally adjustable member H provided with a conical face I for cooperation with the face G on the pulley. The pulley F is fixed upon a hollow spindle K and the member H upon a hollow spindle L surrounding the spindle K and separated therefrom by suitable anti-friction means, such as rings 50 M and N. Suitable lubricating means, such

as oil or grease cups O, fitted in the bearings B and C provide a necessary lubrication for the spindles K and L.

The driving wrench E consists of a hollow housing or supporting frame P fixed to the hollow spindle L in any desired manner so as to be rotatable therewith, and the front end of said housing or frame P is provided with or supports a central wrench socket Q adapted to engage a nut to run the same 65 up upon a screw-threaded member.

The wrench mechanism is primarily designed to apply nuts on pneumatic tire valve stems, either straight or bent, in the course of securing such stems to pneumatic tire tubes, at which time it is customary to also apply a bridge washer or spreader on the valve stem between the tube and the clamping nut which holds the stem on the tube. The valve stem R as conventionally 70 formed has opposite flat faces, best shown in Fig. 3, and the bridge washer S is formed with a central opening of substantially the same configuration and size as the cross sectional contour of the valve stem, so that when it is placed thereon it is non-rotatable on said stem but adapted to easily slide thereover. The bridge washer is also conventionally formed with oppositely inclined, 75 tapered ends or wings s which incline away from the pneumatic tube when affixed on a valve stem. Because of the form and mounting of the bridge washer, it is adapted to cooperate with means preferably positioned adjacent the wrench socket to hold the valve 80 stem against rotation while the driving wrench runs a nut up on the valve stem.

The means referred to consist of an angular bracket T fixed to the base A and having a face plate T' formed with a central opening t so that the plate may encompass the wrench socket Q and lie substantially flush with the front face thereof. On opposite sides of the central opening t, the plate T' is formed with a recess or depression r' 95 having the same contour as the wings s of the bridge washer S and adapted to receive said wings and hold the bridge washer against movement with its inner face in contact with the plate T'. A bridge washer mounted upon a valve stem and held with its wings in the depressions will serve to hold the valve stem against rotation when a nut is being screwed thereon by the socket wrench Q. A bridge washer so held is also 100 105 110

adapted to further cooperate with means located in back of the wrench socket Q to provide proper alignment for the bridge washer with relation to the pneumatic tube, the flat 5 surfaces on the valve stem and the bent arm of a valve stem.

The means herein shown, provide for the alignment of the bent arm of a valve stem and bridge washer, and consists of a bifurcated bracket U fixed against rotation by being secured to a spindle V concentric with the hollow spindles K and L and fixed in a bearing W carried by the base A, by a set screw w. The bifurcated arms of the bracket 15 U are arranged in alignment with the opening in the socket member Q, and the inner left wall of the bracket (in Fig. 3) bears such relation to the bent arm of the valve stem, when positioned therein, that when said 20 bent arm is in contact therewith, the axis of the bent arm will lie in a plane at right angles to the flat surfaces on the valve stem and the center line of the socket t' which holds the bridge washer against movement. 25 To facilitate the insertion of the bent valve stem, the lower edges of the bifurcated arms are preferably chamfered, as shown at u. A valve stem when so inserted will be prevented from rotating independently of the 30 bridge washer or where no bridge washer is used, when a nut which has been first slipped over the bent arm is run up on the stem by the driving wrench E. Obviously, suitable means may be provided to the rear of the 35 wrench socket to hold a straight valve stem against rotation independently of the bridge washer.

Operation: The yielding cone clutch G, I is the first adjusted to yield or slip when a 40 predetermined torque is applied to the member H transmitted by the wrench socket Q. The wrench mechanism is then set in rotation by any form of motive power being applied to the pulley F. A valve stem having 45 its foot portion inserted in the valve opening of an inner tube and a bridge washer S slipped over said stem is then provided with a clamping nut which is started on the screw thread. The end of the stem and nut are 50 then inserted into the wrench socket Q and the bridge washer held in the depressions t' in the face plate T'. The bridge washer, when thus positioned and held, will hold the valve stem against rotation and the socket 55 member will run the nut up on the valve stem into engagement with the bridge washer to clamp the inner tube on the valve stem. In this operation the operator, of course, will hold the collapsed pneumatic tube so 60 that the bridge washer will lie parallel with the side of the tube. For this purpose, the top edge t² of the plate T' is made horizontal to act as a guide. This operation, it will be understood, will be equally applicable 65 with straight or bent valve stems. Since

there is slight rotational play between the bridge washer and the valve stem, the latter may vary slightly in axial position with relation to the bridge washer, but this is of no practical disadvantage in the case of straight 70 valve stems.

Where it is desired, however, to accurately align all of the parts, we provide a means adapted to engage the nipple end of the valve stem and hold it against turning. This 75 is of most value in connection with bent valve stems where a difference in angular relation would cause the bent nipple end to project slightly out of plane at right angles to the wheel. Such a means is the bracket 80 U. Obviously, this bracket or its equivalent may be used alone to prevent turning of the valve stem, particularly where no bridge washer is used.

In the foregoing description it will be obvious 85 that the bridge washer sockets s will equally well accommodate a spreader, hence, where the term bridge washer is here used, spreaders are also intended to be covered thereby.

While we have shown and described the preferred embodiment of our invention, it will be understood that we do not wish to be limited to the specific disclosure, since modifications thereof may be resorted to without departing 95 from the spirit of the invention.

What we claim is:

1. A wrench mechanism, comprising a driving wrench having a wrench socket, a drive mechanism for said driving wrench and means adjacent the wrench socket adapted to cooperate with a bridge washer on a valve stem to hold the valve stem against rotation while the driving wrench runs a nut up thereon.

2. A wrench mechanism, comprising a driving wrench, a drive mechanism for said driving wrench, means for holding a screw-threaded valve stem or the like, having opposite flat faces against rotation while the driving wrench runs a nut up on the screw threads of the valve stem, said means comprising a member having depressions adapted to receive the wings of a bridge washer positioned on the valve stem, said bridge washer having an opening therein and being provided with opposite straight sides engaging over the flat faces on the valve stem.

3. A wrench mechanism, comprising a driving wrench having a wrench socket, a drive mechanism for said driving wrench, a fixed plate having an opening in alignment with the wrench socket, and depressions in the front face of the plate on opposite sides of the opening adapted to receive and hold the wings of a bridge washer mounted upon a valve stem, while the driving wrench runs a nut up on the valve stem.

4. A wrench mechanism, comprising a driving wrench having a wrench socket, a

drive mechanism for said driving wrench, a fixed plate having an opening in alignment with the wrench socket, the front face of the plate lying substantially flush with the 5 front face of the wrench socket, and depressions in the front face of the plate on opposite sides of the opening adapted to receive and hold the wings of a bridge washer mounted upon a valve stem, while the driving 10 wrench runs a nut up on the valve stem into engagement with the bridge washer.

5. A wrench mechanism, comprising a driving wrench consisting of a rotatable supporting frame having at its free end a wrench 15 socket, a drive mechanism for said supporting frame, and said supporting frame being enlarged in the rear of the wrench socket and adapted to accommodate the bent arm 20 of a bent or curved valve stem or the like while the driving wrench runs a nut up on the unbent portion of the valve stem.

6. A wrench mechanism, comprising a driving wrench consisting of a rotatable supporting frame adapted to accommodate 25 therein both the unbent and bent portions of a bent or curved valve stem or the like and having at its front a central wrench socket through which said bent arm can be inserted 30 into the supporting frame, a yielding drive mechanism for said supporting frame and a stationary abutment within said supporting frame to the rear of the wrench socket for

holding the bent arm of a bent or curved valve stem or the like against rotation while the driving wrench runs a nut up on the unbent portion of the valve stem. 35

7. A wrench mechanism, comprising a driving wrench, a drive mechanism for said driving wrench, means for holding a bent valve stem or the like against rotation while 40 the driving wrench runs a nut up on the unbent portion of the valve stem, and means for aligning a bridge washer on the valve stem with relation to a pneumatic tube to which the valve stem is connected and to the 45 bent arm of the valve stem.

8. A wrench mechanism, comprising a driving wrench, a drive mechanism for said driving wrench, an abutment for holding a bent valve stem or the like against rotation 50 while the driving wrench runs a nut up on the unbent portion of the valve stem, and means for aligning a bridge washer on the valve stem with relation to a pneumatic tube to which the valve stem is connected and to the 55 bent arm of the valve stem, said means comprising said abutment against which the bent arm of the valve stem abuts and a member having depressions for holding the bridge washer against rotation. 60

In witness whereof, we have hereunto signed our names.

JOHN WAHL.
OTTO MELZER.
